HYDRAULIC OPERATOR

William A. Ray, North Hollywood, Calif., assignor to General Controls Co., a corporation of California

Application December 6, 1956, Serial No. 626,740

2 Claims. (Cl. 60—52)

This invention relates to hydraulic apparatus including a motor driven pump for creating liquid pressure to perform work. The pump and the motor are enclosed in a common chamber which also forms a reservoir for the liquid. A form of this type of apparatus is described in a prior application, filed June 6, 1955, under Serial No. 513,423, in the name of William A. Ray.

In that prior application, the liquid pressure created by the pump is caused to move an actuator in a linear direction for operating a load, such as a furnace damper or the like. This is accomplished by subjecting a movable wall, such as a diaphragm, to the liquid pressure. When the load has been moved to its desired position, a limit switch is operated by the actuator to deenergize the motor that drives the pump. In this position, the liquid is prevented from flowing out of the pressure chamber bounded by the flexible wall, and the actuator is thereby maintained in its operating position.

When it is desired to return the damper to its original position, a relief valve is caused to open, permitting return of the liquid from the diaphragm chamber into the reservoir.

It is one of the objects of this invention to improve in general this type of apparatus.

It is another object of this invention to provide a more compact and simple arrangement for the elements of the apparatus, and especially by providing an angularly movable actuator instead of a linearly movable one, and located in the reservoir chamber.

This invention possesses many other advantages, and has other objects which may be made more clearly apparent from a consideration of one embodiment of the invention. For this purpose, there is shown a form in the drawings accompanying and forming a part of the present specification. This form will now be described in detail, illustrating the general principles of the invention; but it is to be understood that this detailed description is not to be taken in a limiting sense, since the scope of this invention is best defined by the appended claims.

Referring to the drawings:

Figure 1 is a longitudinal sectional view of an apparatus incorporating the invention;

Figs. 2, 3 and 4 are sectional views taken along planes corresponding to lines 2—2, 3—3 and 4—4 of Fig. 1; and

Fig. 5 is a simplified diagrammatic illustration of the apparatus to indicate the relative arrangements of the essential elements.

A housing or casing 1 serves to contain oil or other suitable liquid indicated by reference character 2 in Figs. 1 and 4. This casing 1 conveniently supports a frame 3 which may be a casting. This frame is supported as by the aid of screws 4 engaging in the bosses 5 extending upwardly from the bottom wall of the casing 1.

Integrally formed on the frame 3 is a pump structure 6. This pump structure 6 may be made substantially identical with the pump structure described and claimed in the said prior application. It has an outlet nipple 7 to which is coupled a flexible hose 8. This flexible hose

8 is bent arcuately to discharge through a nipple structure 9 to ports 10 and 11 (Fig. 4). These ports lead to the lower end of a cylinder 12 mounted in the frame 3. The upper end of the cylinder 12 is closed by a cover 13, formed by a casting.

Located within the cylinder 12 is a piston structure 14 (Fig. 4). This piston structure is vertically movable within the cylinder 12. An O-ring 15 located in the groove in the piston structure 14 precludes the entry of liquid past the piston structure 14 to the upper portion of the piston structure 14.

The piston structure 14 carries a bar 16 extending through a clearance aperture in the cover 13. This bar may be circular in cross-section as indicated in Fig. 3. Its upper portion is formed with teeth to provide a rack 17 engaging the teeth of a gear segment 18.

Accordingly, when the liquid under pressure enters the lower portion of cylinder 12 via ports 10 and 11, the piston structure 14 is urged upwardly to urge the gear segment 18 in a counterclockwise direction. This gear segment is shown as appropriately mounted upon a horizontal shaft 19 as, for example, by the key 21. A pair of spring rings 20 (Fig. 1), cooperating in grooves in shaft 19, confine the segment 18 against axial movement.

In order to guide the bar 16 in its vertical reciprocating movement, use is made of a guiding roller 22 (Figs. 3 and 4) having a concave face corresponding with the cylindrical surface of the bar 16. This roller is mounted for free rotation by the aid of a pin 23 extending across ears 24. These ears 24 are shown as integral with the cover 13.

In order to provide a connection between the bar 16 and the piston 14, the bar 16 is provided with a hemispherical base 36 forming an annular shoulder around the bottom end of the bar 16. Engaging the shoulder is a ring 37. Disposed above the ring 37 is a washer 38. A spring ring 39 serves to hold the ring 37 and the washer 38 in place.

The manner in which the shaft 19 is supported will be described hereinafter. It is sufficient for the present to note that the axis 25 of the shaft 19 (Fig. 1) is horizontal and extends somewhat above the oil level 26.

The counterclockwise movement of segment 18 is opposed by a coil spring 27 (Figs. 1 and 3) disposed around the shaft 19. The left-hand end 28 of this coil spring, as shown most clearly in Figs. 1, 3 and 4, is anchored to the segment 18. Its right-hand end 29 is upturned to engage a hook at the top of a standard 30. This standard 30 may be conveniently mounted on the frame 3 by one of the screws 4 that hold the frame 3 in position on the bosses 5.

The pump structure 6 is operated by the aid of an electric motor 31 having stator laminations 32 and a rotor 33 (Figs. 3 and 4). This rotor is coupled to the pump by the aid of a link 35 having its upper end eccentrically mounted on the shaft of the rotor 33.

The motor 31 may be resiliently mounted on the frame 3 as by the aid of a plate 40 between the rubber elements 41 (Fig. 1) disposed between the heads of the mounting screws 42 and frame 3.

As described in said prior application, when it is desired to rotate the shaft 19 in a counterclockwise direction from the position shown in Fig. 4, oil under pressure is fed through the ports 10 and 11 to elevate the piston 14. This movement results in winding up of the coil spring 27. If it is desired to hold the rack 17 and piston 14 in elevated position, motor 31 is deenergized, and a relief valve 43a from cylinder 12 (Fig. 5) is kept closed. When it is desired to release the rack 17, the relief valve 43a is opened, permitting escape of oil from the space beneath the piston 14 back to the casing 1. Control of the relief valve is effected by an electromagnet structure 43.

The casing 1 is covered by the fluid-tight cover member 44. Cooperating flanges on the casing 1 and the cover member 44 serve for the accommodation of the screws 45. A gasket 46 may be interposed between these two members. The left-hand end of shaft 19 projects out of the casing 1 for connection to an operator or actuator 47. Thus, to facilitate such a connection, the extreme left-hand end of the shaft 19 is shown as being non-circular, upon which a disk 48 is mounted. This disk abuts against a shoulder 49 formed between the non-circular end and the shaft. A central screw 50 is threaded into the end to hold the disk 48 in place.

The shaft to the right of shoulder 49 is flattened on both sides as indicated at 51 (Fig. 2). Connection between the actuator 47 and the disk 48 may be effected by the screws 52, passing through the upper portion of the actuator and threaded into the disk 48. This disk may have a boss 48a engaging within an aperture in the actuator 47.

The flattened portion 51 of shaft 19 serves to key a cam 53 to the shaft 19. The cam 53 is held in place against the shoulder defined by this portion 51 by the aid of a spring ring 54.

The shaft 19 may be appropriately supported in any desired manner by the side walls of the casing 1. In the present instance, it is shown as supported by a pair of needle bearing structures. Each needle bearing structure includes a bearing housing 55 having an external threaded periphery and supporting the needle bearings 56. The bearing housing 55 is appropriately held in place by the aid of a nut 57 disposed inside the casing 1, and threaded on the threads of the housing 55. The flange 58 of housing 55 and nut 57 thus clamp against the wall of casing 1, and sealing washers 57a are provided between these elements and the wall.

The nut 57, as well as the flange 58 of housing 55, have peripheries readily capable of being grasped by the fingers for removing or replacing the bearing structure. A split ring 59 serves to limit the inward movement of each housing and appropriate packing provisions indicated generally by reference character 60 are provided for maintaining a seal around the shaft 19.

As shown most clearly in Figs. 1 and 2, the cam 53 causes angular movement of a shaft 61 adapted to operate a plurality of switch mechanisms 62, 63 and 64. These switch mechanisms are mounted upon an insulation base 65 supported on posts 66 extending from the cover member 44. The cover member 44 is provided generally with a peripheral wall 67 over which extends a sheet metal cover 68 for housing the switch mechanisms.

Each of the switch mechanisms is provided with a push rod or button 69 adapted to be urged inwardly by the associated spring arm 70. Each arm 70 is mounted at its left-hand end, as viewed in Fig. 2, so as to permit it to be flexed by a corresponding cam 71. Each cam 71 contacts the corresponding arcuate cam follower 72 mounted upon the lower surface of the arm 70. Each of these cams 71 is mounted upon the shaft 61. The shaft 61 may be appropriately journaled in brackets 73 formed integrally with the cover member 44.

One of the plurality of circuit controllers 62, 63 or 64 can operate as a limit switch for deenergizing the motor 31.

The shaft 61 is moved by the aid of the arm 73a fastened to the shaft 61 and carrying a cam follower roller 74 for cooperation with cam 53. This arm 73a extends through an opening 75 in that portion of the cover 44 which extends beyond the casing 1.

Those circuit controllers 62, 63 and 64 which are not

utilized as a limit switch, may be used to control auxiliary circuits, such as for controlling blower motors or valves.

When it is desired to operate a load, the circuit for motor 32-33 is energized as by closing a switch. This circuit includes one of the circuit controllers 62, 63 or 64. The motor operates pump 6, the relief valve 43a being closed. Accordingly, oil under pressure is supplied through ports 10 and 11 beneath the piston 14 to elevate it and thereby to operate rack 16; this causes pinion segment 18 to move in a counterclockwise direction. This movement is resiliently opposed by spring 27.

Actuator 47 is correspondingly moved. The cam 53, at appropriate points of angular travel of shaft 19, operates the circuit controllers 62, 63, 64, one of which 15 interrupts the circuit for motor 32-33. The relief valve 43a remaining closed, the piston 14 is retained by fluid pressures in its elevated position. When it is desired to return the actuator 47 to its final position, the relief valve 43a is opened by energization of electromagnet 43. The 20 oil under piston 14 then can escape into the body of liquid 2, via this relief valve.

The inventor claims:

1. In a hydraulic operator: a container; a body of lubricating liquid in the container; a shaft extending across 25 the container and having a horizontal axis; said shaft having a portion extending beyond the container; bearing structures for the shaft, and supported on opposite walls of the container; a pinion carried by the shaft, and within the container; means for resiliently urging the pinion 30 angularly in one direction; a rack having teeth engaging the pinion for urging the pinion in the opposite direction, said rack being located in the casing; a piston connected to the lower end of the rack; a cylinder in which the piston operates; said cylinder being disposed so that its lower 35 portion is below the level of the liquid in the container; said cylinder having an upper opening through which the rack extends with clearance, and through which opening liquid from the container may pass an electric motor having a rotor, and at least partly immersed in the liquid; a 40 pump for the liquid operated by the motor and entirely immersed in the liquid; means in the container for forming a supply port from the pump to the cylinder and a relief port from the pump to the liquid; means controlling the relief port; a removable sealing cover for the container; an actuator coupled to that portion of the shaft 45 which extends from the container; a cam also mounted on said portion; an arm moved by the cam; an auxiliary shaft upon which the arm is mounted; cam members spaced along the auxiliary shaft and carried thereby; and one or more circuit controllers operated by the movement of the cam members mounted on said auxiliary shaft, at least one of said circuit controllers serving to 50 control energization of the motor.

2. The combination as set forth in claim 1, with the addition of a housing for the circuit controllers, the auxiliary shaft, and the cam members, said housing being carried by the cover, and having an opening through which the arm extends.
